UNITED STATES PATENT OFFICE.

BENJAMIN F. LOWRY, OF AUSTIN, TEXAS.

FUEL-SUPPLY SYSTEM AND STARTER FOR EXPLOSIVE-ENGINES.

1,120,828.

Specification of Letters Patent.

Patented Dec. 15, 1914.

Application filed December 30, 1913. Serial No. 809,562.

To all whom it may concern:

Be it known that I, BENJAMIN F. LOWRY, a citizen of the United States, residing at Austin, in the county of Travis and State of Texas, have invented a new and useful Fuel-Supply System and Starter for Explosive-Engines, of which the following is a specification.

This invention relates to improvements in a fuel supply system for explosive engines.

An object of the present invention is to provide a fuel supply system in which the heat of the exhaust gases will be utilized to vaporize the liquid fuel with which they directly contact so that the carburetor and auxiliary devices of this character may be dispensed with.

A further object is to provide a fuel supply system for internal combustion engines in which all, or a portion of the exhaust gases will be returned to the cylinder with a proper amount of air and fuel mixed therewith.

A further object is to provide a system in which the exhaust gases will be passed one or more times through the cylinder so that any unburned portion thereof will upon its second passage through the explosion cylinder be burned and the power contained therein utilized.

A further object is to provide a producer system supplying combustible gases under pressure to a two cycle internal combustion engine so that the carburetor may be dispensed with and in which the explosive mixture need not be compressed in the crank case prior to its ejection into the cylinder.

A further object is to provide a gas producer and supply system as above mentioned and which provides an explosive mixture which may be injected into the cylinder for the starting thereof.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawing accompanying this specification and forming a part thereof, the

preferable embodiment of my invention is illustrated, in which:

The figure is a plan view of my improved apparatus comprising the fuel supply system.

Referring to the drawing, 1 is an engine bed upon which is mounted an internal combustion engine including a cylinder 2, crank shaft 3 and fly wheel 4. The engine is of the two cycle type and includes the usual allotment of valves and valve gears, the exact details of which, however, will not be treated in detail.

The crank shaft 3 of the engine is prolonged and provided with the crank arm 5 to which is secured the piston rod 6 of an air or fuel compressor 7. Thus the air or fuel compressor 7 is mechanically connected to and operated by the internal combustion engine. It is to be noted however that the air compressor may be driven through the intervention of suitable gears, a belt, or other suitable means, should it be so desired. It is to be noted in this connection that if the compressor be driven by gears or belts, the storage capacity of the pipe 11 will be sufficient to act as a reservoir for the exhaust gases prior to this admission into the compressor 7.

A fuel storage tank 8 is provided and is of considerable capacity and is designed to withstand high pressures so that the mixture which is stored therein may be subjected to and maintained at relatively high pressure so that it will be properly delivered to the cylinder 2 through the inlet pipe 9.

The fuel storage tank is provided with the fresh air relief valve 10 so that a safety valve will be had should the pressure within the tank arise to excessive values. The exhaust pipe 11 which leads from the cylinder 2 is also provided with a pressure relief valve 12.

The exhaust pipe 11 communicates with the inlet side of the compressor 7 so that the exhaust gases will be drawn into the compressor and expelled therefrom under pressure through the storage tank inlet pipe 13. A pipe 14 also communicates with the inlet side of the compressor, and is adapted to supply a quantity of air thereto. The air inlet pipe 14 is provided with a suitable controlling

valve 15 whereby the quantity of air admitted may be properly regulated. A fuel inlet pipe 16 also communicates with the compressor and is controlled by the valve 17. The compressor is provided with the automatic inlet valves 18 which are arranged in front of and control the air, fuel and exhaust gases admitted to the compressor. The storage tank inlet pipe 13 is also provided with an automatic valve 19 and which forms a part of the compressor and takes the place of the ordinary outlet valve. A governor 20 communicates by means of the pipe 21 with the inlet pipe 13 of the storage tank and is subjected to the storage tank pressures. The governor is provided with the rod 22 which contacts with and holds in a seated condition the automatic inlet valves 18 when the pressures within the storage tank arise above a predetermined value. The governor at the same time opens the compressor to the atmosphere through the valve 23 so that the compressor will not offer any great resistance to the rotation of the crank shaft 3. In this connection it is to be noted that the rod 20' is carried by the governor 20 and connects with and operates the valve 23. As the governor is moved inwardly by the pressure exerted thereupon from the pipe 21, the rod 20' is also moved and moves the valve 23 beyond the opening in the cylinder wall which thus provides for the free ingress and egress of air to the cylinder 7. The operation of my improved system is substantially as follows:—Considering that a charge has been fired within the cylinder, it will exhaust through the pipe 11 and due to the fact that the compressor piston is moving in an opposite direction to the engine piston the exhaust gases will be drawn into the compressor cylinder. Also a quantity of air and fuel will be drawn in the compressor cylinder and the entire mixture compressed and injected in the storage tank 8. The exhaust gases due to their high temperature will volatilize the fuel and a mixture of exhaust gases, fuel and air will be stored within the tank 8 under a suitable pressure. The said gas will be delivered to the engine upon the opening of the inlet valve thereof and due to the gaseous condition of the mixture, no carburetor will be necessary. The mixture will then be fired and the cycle of operation will again occur. As each charge is fired the pressure rises until it finally reaches the desired amount, at which time the relief valve 10 will operate and allow for the escapement of a certain quantity of gaseous mixture from the storage tank. However, such escapement would represent a waste of fuel and for which reason the governor and relief valves 12 have been provided. As the pressure approaches the desired amount, the gov-

ernor 20 will operate and prevent a further amount of fuel, air, and exhaust gases from being delivered to the tank. When the governor so operates the compressor will be opened to the atmosphere so that air may pass into and radially therefrom. The pressure relief valve 12 provides a suitable escapement for the exhaust gases. Thus should the exhaust gases contain some unburnt fuel after passing through the cylinder they will in all probability be burned upon the next cycle of operation. The gas within the tank 8 may be utilized for various other purposes other than the running of an engine as for instance, for lighting or heating purpose, if so desired.

It is to be noted that by providing the storage tank 8 with a combustible and compressed gas, the engine may be easily started by manually opening the inlet valve of the engine cylinder, allowing a quantity of explosive gases to be injected therein and moving the exploding device so that the mixture will be exploded and the engine easily started, or the engine may be started by merely utilizing the compression of the gases within the storage tank 8 similar to an ordinary air compression starter.

The engine has been illustrated with one cylinder, but it is to be understood that the system herein disclosed can be used with multi-cylinder engines.

Having thus described my invention, what I claim is:—

1. A fuel supply system including an internal combustion engine, a fuel inlet communicating therewith and an exhaust outlet leading therefrom, a storage tank communicating with the said engine fuel inlet, a compressor communicating with and adapted to deliver compressed gases to said storage tank, said engine exhaust outlet communicating with said compressor, fuel and air pipes communicating with said compressor, a pressure relief valve communicating with said exhaust pipe, and a governor controlling the pressure within said storage tank.

2. A fuel supply system including an internal combustion engine, a fuel inlet communicating therewith and an exhaust outlet leading therefrom, a storage tank communicating with the said engine fuel inlet, a compressor communicating with and adapted to deliver compressed gas to said storage tank, said engine exhaust outlet communicating with said compressor, fuel and air pipes communicating with said compressor, a pressure relief valve communicating with said exhaust pipe, a governor controlling the pressure within said storage tank, and a pressure relief valve communicating with said storage tank.

3. An apparatus including an internal combustion engine, a compressor, and a

storage tank, said tank communicating with the outlet of said compressor and with the inlet of said engine, the exhaust of said engine communicating with the inlet of said compressor, air and fuel pipes communicating with the inlet of said compressor, automatic valves controlling the inlet and outlet of said compressor, and a governor controlled by and communicating with the said tank, said governor engaging the compressor inlet valves adapted to hold the same in a seated position, and means for relieving the exhaust pressure of said engine when the governor has closed the outlet thereof.

4. An apparatus of the class described comprising an internal combustion engine, a compressor mechanically connected thereto and with the piston thereof in opposite phase relation with the piston of the said

engine, a fuel storage tank communicating with the inlet of the engine and with the outlet of the compressor, the exhaust of said engine communicating with the inlet of said compressor, air and fuel supply pipes communicating with the inlet of said compressor, a pressure relief valve disposed in the engine exhaust pipe, and a governor communicating with the said tank adapted to close the said air, fuel and exhaust pipes and to open said compressor to the atmosphere.

In testimony that I claim the foregoing as my own, I have hereto affixed my signature in the presence of two witnesses:

BENJAMIN F. LOWRY.
